UNITED STATES PATENT OFFICE.

PHILIP F. LENHART, OF BROOKLYN, NEW YORK.

BACKWATER AND SEWER-GAS TRAP.

SPECIFICATION forming part of Letters Patent No. 542,417, dated July 9, 1895.

Application filed November 21, 1894. Serial No. 529,439. (No model.)

To all whom it may concern:

Be it known that I, PHILIP F. LENHART, a citizen of the United States, residing at Brooklyn, in the county of Kings and State of New York, have invented certain new and useful Improvements in Backwater and Sewer-Gas Traps, of which the following is a specification.

This invention relates to certain improvements in sewer-traps of that class in which a swinging valve is used, which opens readily to interior pressure but closes tightly by gravity and exterior pressure, so as to prevent the ingress of backwater and sewer-gas, the trap being furthermore so arranged as to be readily accessible for cleaning and repairs; and the invention consists of a backwater and sewer-gas trap provided with a swinging valve, which is located in an inclined guide-box that is formed of angular abutting flanges on the two adjacent pipe-sections of the valve-casings, said flanges being connected by bolts. The outer pipe-section is provided with a straight and enlarged top part for permitting the swinging of the valve which is hinged to an inclined valve-frame inserted in the guide-box, which valve-frame is made removable from the guide-box and formed of two sections, the inner one having a seat for the valve which is hinged to the upper part of the outer section, as will be fully described hereinafter.

In the accompanying drawings, Figure 1 represents a vertical longitudinal section of my improved backwater and sewer-gas trap. Fig. 2 is a top view of the same. Fig. 3 is an elevation of the inner pipe-section, showing the valve-frame in partly raised position; and Fig. 4 is a side elevation showing the trap arranged on a smaller scale, so as to be used for sinks, basins, &c.

Similar letters of reference indicate corresponding parts.

Referring to the drawings, a a' represent the casing of my improved sewer-gas trap, which is inserted in the usual manner into the pipe connecting the sewer with the house, so as to protect the same against sewer-gas and against overflow by backwater from the sewer. The valve-casing is made of two pipe-sections a a' , an inner section a back of the valve B and an outer section a' in front of the valve B . The sections a a' are united at a suitable angle of inclination to the longi-

tudinal axis of the trap by means of inclined angular flanges a^2 , which are connected at their upper and lower ends by screw-bolts a^3 . 55 A suitable packing is interposed between the faces of the flanges at their sides and bottoms.

The inner section a of the valve-casing is made of a somewhat smaller diameter than the outer section a' , which latter is enlarged 60 at its upper part and provided with a straight inclined portion a^4 , so as to give sufficient play for the valve B when the same is swinging into open position. The valve B is hinged to eyes b at the upper end of a valve-frame 65 C C' , which is formed of two sections, an inner section C , which is of the same diameter and in line with the inner pipe-section a of the valve-casing, and an outer section C' , which is in line with the inner surface of the 70 outer section a' . The inner section C' of the valve-frame is provided with a seat d of type-metal, while the valve B is made of composition that is not liable to corrosion by the action of fluids on the same. Both sections 75 C C' of the valve-frame are inserted into the open top part and supported by the sides and closed bottom part of the inclined guide-box formed by the angular flanges a^2 of the pipe-section a a' , the valve-frame being 80 tightly retained in the oblong opening formed by the inclined guide-box. The upper part of one of the sections is provided with a handle h , so that when the connecting-screws 85 a^3 are loosened the entire valve-frame can be readily removed, so as to permit the cleaning of the valve and its valve-frame, while giving access to the pipe-sections a a' , so as to dispense with the hand-hole and hand-hole cover heretofore used in traps of this 90 class, as the opening in the top of the guide-box a^2 is large enough to permit the introduction of the hand and arm for cleaning the pipe-sections a a' of obstructions or sediments. When any liquid is passed through 95 the trap the valve is moved into open position, so as not to obstruct the outflow of the drainage, while it effectually prevents the flow of backwater, partly by gravity and partly by the back-pressure on the valve, so 100 that it closes tightly against its seat and prevents the passage of backwater and sewer-gases into the service-pipes of the building. As the valve swings freely out of the way of

the outflow, no sediments are formed around the valve which would prevent the proper closing of the same against backwater and sewer-gas. The valve can also be constructed 5 on a smaller scale, as a trap for wash-basins, sinks, &c., in which case the connection of the pipe-sections, instead of being made by calking, as in large-sized traps, is made by unions with the connecting-pipes, as shown 10 in Fig. 4. The same advantages result in this case—namely, the convenience of removing the valve and its valve-frame, so as to give access to the valve and to the interior of the valve-casing for cleaning, and the reliability 15 by which the trap accomplishes its functions of opening to the outflow of the drainage and of closing against backwater and sewer-gases. As the valve proper is made of non-corrodible composition metal and the valve-seat 20 of type-metal, the valve and the seat are not affected by the liquids and gases passing through the trap, and the same is rendered thereby much more durable than the cast-metal valves used in sewer-traps heretofore. 25 Having thus described my invention, I claim as new and desire to secure by Letters Patent—

1. The combination of a valve-casing, formed of an inner and an outer pipe-section, 30 said pipe-sections being provided with exterior, angular flanges forming a guide-box open at the upper end, bolts for connecting said flanges, and a valve-frame inserted into the open top-part of the guide-box and provided with a valve-seat and with a valve 35 hinged to the upper part of the frame, substantially as set forth.

2. The combination of a valve-casing, formed of an inner and an outer pipe-section, said pipe-sections being provided with 40 exterior, angular flanges forming a guide-box, bolts for connecting said flanges, and a valve-frame inserted into the open top-part of the guide-box and formed of two sections, the inner section being provided with a valve-seat and the outer section with a valve which is hinged to its upper part, substantially as set forth. 45

3. The combination of a valve-casing, composed of an inner and outer pipe-section 50 united at a suitable angle of inclination to the longitudinal axis of the casing, said pipe-sections being provided with inclined angular flanges abutting at the sides and bottom and being open at the top, bolts for connecting 55 said flanges, a valve-frame guided by said inclined flanges, and composed of two sections, one section being of the same interior diameter as the inner pipe-section of the valve-casing, while the outer section is in line with 60 the interior surface of the enlarged outer pipe-section of the valve-casing, and a valve hinged to the upper part of the outer section of the valve-frame and adapted to swing in the enlarged upper part of the outer pipe-section, 65 substantially as set forth.

In testimony that I claim the foregoing as my invention I have signed my name in presence of two subscribing witnesses.

PHILIP F. LENHART.
